FLUID PUMP

Henry Ford, Dearborn, Mich., assignor to Ford Motor Company, Dearborn, Mich., a corporation of Delaware

Application May 1, 1933, Serial No. 668,710

3 Claims. (Cl. 103—103)

The object of my invention is to provide a fluid pump of simple, durable, and inexpensive construction. The specific pump shown is designed for use on an internal combustion engine to circulate the cooling water from the engine and through the radiator; however, the novel features incorporated in my pump may be readily adapted for use in pumps of other design and for other purposes without departing from my invention.

More specifically, the object of my invention is to provide a centrifugal pump having an impeller rotor therein characterized in that the ordinary fibrous packing material is eliminated and a metal to metal seal substituted therefor which prevents the fluid from flowing around the impeller and out through the pump shaft bearing. This seal is disk-shaped and is provided with means for supplying just enough oil to the coacting surfaces to lubricate same. This restriction in the flow of oil to the seal surfaces is necessary in order that the centrifugal action of the seal does not throw out large amounts of oil into the fluid stream thereby diminishing the oil supply and contaminating the fluid circulated by the pump.

A further feature of my improved pump is that the impeller is rotatably mounted within the fluid chamber independently of the pump shaft, the rear face of the impeller forming one surface of the water seal and which impeller is resiliently urged against the fluid seal by means of a spiral spring which is anchored in the pump housing. A universal joint connects the impeller with the pump shaft so that axial deflections of the shaft in no way tend to affect the functioning of the water seal, as invariably results where the impeller is fixed to or mounted upon the pump shaft.

With these and other objects in view, my invention consists in the arrangement, construction and combination of the various parts comprising my improved device, as described in the specification, claimed in my claims, and illustrated in the accompanying drawing, in which:

Figure 1 shows a central cross-sectional view through my improved pump, illustrating the several elements comprising same.

Figure 2 shows an end view of my pump impeller, and

Figure 3 shows an end view of the spring which resiliently urges the impeller axially to form the fluid seal.

Referring to the accompanying drawing, I have used the reference numeral 10 to indicate generally a pump housing which is provided with a

flange 11 cast integrally therewith and which flange is adapted to be bolted to the cylinder head 12 of an internal combustion engine. It will be noted that the flanged wall of the housing 10 is provided with a central opening 13 which is aligned with a corresponding opening in the cylinder head 12. The fluid circulated is thus drawn from the cylinder head into the pump housing through these openings.

In position axially aligned with the opening 13, but in the opposite wall of the housing, I have machined a cylindrical impeller bearing 15. This bearing does not extend through the adjacent wall of the housing but is closed by a disk-shaped impeller seat 14 which is formed integrally with the housing and which forms one element of the pump's fluid seal. My impeller is a disk-shaped casting 16, one face of which is machined smooth and flat to coact with the seat 14 and the edge of which is machined cylindrical whereby the impeller is rotatably mounted in the bearing 15.

This impeller is installed in position on the seat 14 by inserting it through the opening 13. A pair of diametrically opposed impeller blades 17 extend axially from the back of the impeller into the chamber formed within the housing 10, which blades are cast integrally with a hub member 18. The path described by the blades 17 is shown by dotted lines 19 in Figure 1, from which it may be seen that rotation of the impeller will draw fluid in through the opening 13 and force it outwardly through an opening 36 formed in the upper portion of the housing. It will be noted that the hub 18 is not bored through and that any fluid escaping by other than the openings 13 and 36 must pass through the bearing 15 and fluid seal 14.

In order that this seal may be fluid tight, the impeller is resiliently urged against the seat 14 by a spring 20. This spring, as shown in Figure 3, is of spiral or conical shape; however, the periphery of the spring is truly circular and has a free diameter considerably larger than the opening 13. An internal groove 21 is machined in the edge of the opening 13 into which the outer coil of my spring is anchored. A very important feature of this device is that when the spring is snapped into position in the groove 21 almost the whole outer coil of the spring rests against the bottom of the groove thereby firmly anchoring the spring into position. This is made possible because, as will be noted in Figure 3, the spring is given an abrupt bend, as shown at 22, the spiral portion of the spring starting at this bend. The center

coil of the spring is tightly wrapped around a button 23, this button being formed of hard steel and having a flat space which abuts the end of the hub 18. The free length of the spring is 5 about half again as long as shown in the drawing whereby the impeller is resiliently urged against the seat 14.

A semi-circular slot 24 is machined in the center of the flat impeller face, this slot being cut 10 with a standard Woodruff keyway cutter. The slot does not extend through the impeller, as there is no passageway whatever between the blade side of the impeller and the slot 24 except along the joint formed by the bearing 15 and seat 14. The 15 slot 24 is provided to form a drive for the impeller.

It will be noted that an oil chamber 25 is cast integrally with the housing 10 and that a pair of openings 27 and 26 extend through the center of the seat 14 and through the outer wall of the oil chamber 25, respectively. These openings are aligned with each other and extend perpendicular to the seat 14. A porous graphite bronze bushing 28 is pressed into the openings 26 and 27 25 and extends therebetween leaving the intermediate portion of the bushing exposed to the lubricant in the oil chamber 25, which chamber is provided with a suitable fitting 30 which permits of ready replenishment of the oil in the chamber.

30 I have provided a shaft 31 which is rotatably mounted in the bushing 28, this shaft having the end adjacent to the impeller 16 flattened at 32 to thereby form a tongue which coacts with the slot 24 and rotatably drives the impeller. A collar 33 is formed integrally with the shaft 31 adjacent to the outer end of the oil chamber and a cap 34 is screwed down over this collar to thereby prevent axial movement of the shaft in the bushing 28. The shaft 31 projects beyond the collar 33 40 and a driving pulley 35 is fastened on this projecting portion of the shaft. The preferred method of forming this shaft is by chill mold die casting with only a subsequent grinding operation.

From the foregoing it will be noted that rotation of the pulley 35 drives the shaft 31 which 45 rotates the impeller 16 by means of the tongue 32. It will also be noted that the impeller 16 is rotatably mounted independently of the shaft 31 so that a considerable axial misalignment of these 50 two elements is permissible without affecting the fluid seal.

It is highly important that the impeller be 55 rotatably mounted independently of the shaft 31 as it is believed impossible to maintain a fluid tight seal with the impeller if the latter is fixed to the driving shaft, the reason being that should one end of the shaft bearing wear slightly more than the other end, due to the side-thrust resulting from the driving belt, the shaft then is not 60 truly perpendicular to the seat 14. In this case the impeller wears to a conical shape and bears only upon one point on the seat 14 thereby allowing fluid to seep through the joint with the rest of the seat surface and thus destroy the purpose 65 of the joint. It is absolutely essential that truly complementary surfaces be maintained at all times between the impeller and the seat 14, as even a clearance of only a fraction of a thousandth of an inch at any point around the seat 70 will allow fluid to seep through the seal.

Another feature of great importance in this device comprises the lubrication system. It is well known that when the impeller is rotating a centrifugal action is set up along the seat 14 which 75 draws the lubricant out from the center of the

impeller and discharges it into the fluid chamber. If the keyway slot 24 were kept filled with oil from the chamber 25 while the pump was rotating a steady stream of oil would be thrown off the periphery of the impeller and not only soon deplete the oil supply but also this action would contaminate the fluid being pumped. To avoid this a novel means is provided whereby a definite but very limited amount of oil is supplied to the fluid seal surfaces.

As has been stated, the bushing 28 is formed of porous material which has a comparatively low elasticity. Consequently, when the bushing is installed in the pump it is essential that it be pressed first through the opening 27 and then 15 into the opening 26 in the direction shown by arrow 29 so that a tight press fit will be secured in the opening 27 although the joint between the opening 26 and the bushing may be somewhat 20 looser.

The tight fit with the opening 27 is essential in order that oil may not be drawn by centrifugal action along the exterior of the bushing and through this opening.

All lubrication for both the shaft and the impeller must filter through the bushing as there is no oil hole or other direct passageway from the oil chamber to the shaft. This feature of the device is highly important in that the amount of oil supplied to the shaft and impeller is regulated 30 by the wall thickness and porosity of the bearing. For this reason, even should the bushing wear an appreciable amount, still only sufficient oil will be supplied to the impeller to maintain an oil film on the seat 14. The advantage of this 35 function may be better appreciated by contrasting it with the conventional pump bushing which supplies oil in an unlimited quantity to the bushing. Consequently, wear in such a bushing would permit the impeller to draw out all the oil in 40 the reservoir in only a very short time.

Referring to the shouldered end of the shaft 31, it will be noted that oil which may seep out between the bushing 28 and opening 26 or along the adjacent bearing surfaces serves to lubricate 45 the collar 33, and while this collar centrifugally throws the oil out to some extent, still the outer side of the collar also acts to centrifugally retain the oil in the cap 34, so that the effect is neutralized. For this reason very little oil escapes 50 from the pulley end of the shaft.

Among the many advantages arising from the use of my improved device, it might be well to mention that this pump is simple and durable and 55 that the quantity of lubricant used is independent of the age or condition of the pump shaft bearing.

Another important advantage results from rotatably mounting the impeller independently of the pump shaft, as such structure maintains the 60 fluid seal even should the bearing wear an excessive amount.

It may be thought that the friction of the button 23 on the end of the impeller would cause 65 excessive wear, due to the absence of oil lubrication; however, it has been found that where the pump is used to circulate liquids that such liquids cool and lubricate a bearing immersed therein so that the wear is not objectionable.

Some changes may be made in the arrangement, construction and combination of the various parts of my improved device without departing from the spirit of my invention, and it is my intention to cover by my claims such changes as 75

may reasonably be included within the scope thereof.

I claim as my invention:

1. A centrifugal pump construction comprising, 5 a pump housing, a drive shaft rotatably mounted in said housing, an impeller rotatably mounted in said housing independently of said drive shaft but in substantial axial alignment therewith, a universal driving connection disposed between 10 said impeller and drive shaft, said impeller having a disc-shaped surface which coats with one wall of said housing to form a water seal therebetween, with said housing having an annular inlet passageway in substantial axial alignment 15 with said impeller, said inlet passageway having an internal groove therein, and a conical shaped spiral spring, the base of which is secured in said internal groove with the apex of said spring abutting the center of said impeller, whereby said 20 impeller is resiliently urged against said housing to form the water seal.

2. A device, as claimed in claim 1, said universal driving connection comprising a Woodruff-type keyway slot in the side of the impeller adjacent to said shaft, and wherein the adjacent end 25

of said shaft is provided with a tongue which engages said slot to form a universal driving connection therebetween.

3. A water pump construction comprising, a 5 pump housing having a drive shaft rotatably mounted therein, a disc shaped impeller having radial extending impeller blades formed on one side thereof with the opposite side of said impeller having a disc shaped surface thereon which coats with an adjacent wall 10 of the housing to form a water seal therebetween, said impeller having its periphery between its disc shaped surface and said impeller blades machined to form an annular cylindrical bearing surface, a second cylindrical bearing formed in 15 said housing upon which said impeller bearing surface is rotatably mounted independently of said drive shaft, a universal drive connection between said impeller and said shaft, said housing having a fluid inlet opening therein axially aligned with the impeller, and a spring extending across said inlet opening to the central portion of said impeller, the fluid being pumped circulating around said spring. 20
